(57) **CLAIM**

I claim the ornamental design for a duvet cover with a removeable pet protection layer, as shown and described.

DESCRIPTION

FIG. 1 is a top perspective view of a duvet cover with a removeable pet protection layer, with the removeable pet protection layer attached, showing my new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof;

FIG. 7 is a rear elevation view thereof;

FIG. 8 is a top perspective view of a duvet cover with a removeable pet protection layer, with the removeable pet protection layer removed, showing my new design;

FIG. 9 is a top plan view thereof;

FIG. 10 is a bottom plan view thereof;

FIG. 11 is a right side elevation view thereof;

FIG. 12 is a left side elevation view thereof;

FIG. 13 is a front elevation view thereof;

FIG. 14 is a rear elevation view thereof;

FIG. 15 is a top perspective view of a second embodiment of a duvet cover with a removeable pet protection layer, with the removeable pet protection layer attached, showing my design;

FIG. 16 is a top plan view thereof;

FIG. 17 is a bottom plan view thereof;

FIG. 18 is a right side elevation view thereof;

FIG. 19 is a left side elevation view thereof;

FIG. 20 is a front elevation view thereof;

FIG. 21 is a rear elevation view thereof;

FIG. 22 is a top perspective view of a second embodiment of a duvet cover with a removeable pet protection layer, with the removeable pet protection layer removed, showing my new design;

FIG. 23 is a top plan view thereof;

FIG. 24 is a bottom plan view thereof;

FIG. 25 is a right side elevation view thereof;

FIG. 26 is a left side elevation view thereof;

FIG. 27 is a front elevation view thereof;

FIG. 28 is a rear elevation view thereof;

FIG. 29 is a top perspective view of a third embodiment of a duvet cover with a removeable pet protection layer, with the removeable pet protection layer attached, showing my design;

FIG. 30 is a top plan view thereof;

FIG. 31 is a bottom plan view thereof;

FIG. 32 is a right side elevation view thereof;

FIG. 33 is a left side elevation view thereof;

FIG. 34 is a front elevation view thereof;

FIG. 35 is a rear elevation view thereof;

(Continued)

FIG. 36 is a top perspective view of a third embodiment of a duvet cover with a removable pet protection layer, with the removable pet protection layer removed, showing my new design;

FIG. 37 is a top plan view thereof;

FIG. 38 is a bottom plan view thereof;

FIG. 39 is a right side elevation view thereof;

FIG. 40 is a left side elevation view thereof;

FIG. 41 is a front elevation view thereof;

FIG. 42 is a rear elevation view thereof;

FIG. 43 is a top perspective view of a fourth embodiment of a duvet cover with a removable pet protection layer, with the removable pet protection layer attached, showing my design;

FIG. 44 is a top plan view thereof;

FIG. 45 is a bottom plan view thereof;

FIG. 46 is a right side elevation view thereof;

FIG. 47 is a left side elevation view thereof;

FIG. 48 is a front elevation view thereof;

FIG. 49 is a rear elevation view thereof;

FIG. 50 is a top perspective view of a fourth embodiment of a duvet cover with a removable pet protection layer, with the removable pet protection layer removed, showing my new design;

FIG. 51 is a top plan view thereof;

FIG. 52 is a bottom plan view thereof;

FIG. 53 is a right side elevation view thereof;

FIG. 54 is a left side elevation view thereof;
FIG. 55 is a front elevation view thereof; and,
FIG. 56 is a rear elevation view thereof.
